UNITED STATES PATENT OFFICE.

EDWARD J. DOLAN, OF PHILADELPHIA, PENNSYLVANIA.

ACETYLENE-GAS TIP.

SPECIFICATION forming part of Letters Patent No. 640,886, dated January 9, 1900.

Application filed January 3, 1899. Renewed August 16, 1899. Serial No. 727,444. (No model.)

To all whom it may concern:

Be it known that I, EDWARD J. DOLAN, a citizen of the United States, residing at Philadelphia, in the county of Philadelphia and 5 State of Pennsylvania, have invented certain new and useful Improvements in Methods of and Processes for Producing a Flat Smokeless Acetylene-Gas Flame; and I do declare the following to be a full, clear, and exact description of the invention, such as will enable others skilled in the art to which it appertains to make and use the same, reference being had to the accompanying drawings, and to the letters and figures of reference marked 15 thereon, which form a part of this specification.

This invention relates to certain new and useful improvements in methods of burning acetylene gas; and the invention has for its 20 object the provision of a method or process whereby a flat and smokeless flame may be produced at all times and under varying degrees of gas-pressure by the use of a single slotted burner, in the construction of which 25 burner no provision is had for the admission of air.

Heretofore it has been found to be impossible to produce a flat and smokeless flame in burning either acetylene gas or other gases 30 which are rich in hydrocarbons in a gas-burner the tip of which has been provided with a single combustion-slot. Various expedients have been resorted to with the view of accomplishing this end; but as far as I have 35 been able to discover no practical method has heretofore been perfected whereby a flat and smokeless flame may at all times and under varying degrees of gas-pressure be assured by the use of a single-tip gas-burner.

With the view of producing a flat flame in 40 burning acetylene gas expensive burners of the "duplex" type have been proposed, the gas-passages at the tips of the burners being small round openings and the two burners 45 being inclined toward one another, so that the two jets of gas upon leaving the burner-tips would impinge upon each other at a point a considerable distance from the burner-tips, and thus produce a flat flame when ignited.

This style of burner has been found to be 50 objectionable on account of the expense incident to manufacture, the tendency of the

minute round openings in the burner-tips to become clogged, and the extreme care that is at all times required to insure the impingement of the gas-jets at the proper angle, as it has been found that the slightest deviation of the meeting jets of gas from proper alinement or deviation from the proper angle of contact will serve to defeat the end in view—*i. e.*, the 60 production of a uniform, flat, and smokeless flame.

Various expedients have been resorted to with the view of producing a single-tip burner adapted for use in producing a flat, uniform, 65 and smokeless flame under varying degrees of gas-pressure. A burner of this general character is shown in Patent No. 597,057, granted to me January 11, 1898, in which burner provision is had for the admission of 70 air into the interior of the burner; but I have found that in practice this plan is impracticable.

The present invention is the result of long-continued experiments in the construction of 75 gas-burners especially designed for burning acetylene gas with the view of producing a flat flame which will at all times and under varying degrees of gas-pressure be absolutely smokeless, and I have discovered as the result of my experiments that a certain fixed relationship or combination must exist between the parts of the burner, in determining which the depth, the width, and radius of the slot, the provision of a gas-chamber communicating with the slot, and other features of construction are necessarily considered, as will hereinafter be more fully described, shown 80 in the accompanying drawings, and then specifically defined in the appended claims.

It is to be understood that the slot is arc-shaped and that by the term "radius of the slot" I mean the distance from the point indicated by the numeral 1 to the point indicated by the numeral 2, as shown in Fig. 3 of the drawings, and that by the term "depth of the slot" I refer to the distance between the point indicated by the numeral 2 and that indicated by the numeral 3 in said Fig. 3 of the drawings. It will be also understood that in 95 no instance in which the depth of the slot is mentioned do I include the widened entrance or space intervening between the upper edge of the slot and the extreme tip of the burner.

The general form of burner which I employ in carrying out my process or method is clearly illustrated in the accompanying drawings, which, with the letters of reference marked 5 thereon, form a part of this specification, and in which drawings—

Figure 1 is a perspective view of a gas-burner embodying my invention. Fig. 2 is a top plan view of the burner shown in Fig. 1. Fig. 3 10 is a vertical section of the burner, taken at right angles to the slot. Fig. 4 is a vertical section taken through the slot of the burner shown in Fig. 1. Figs. 5, 6, and 7 are central vertical sections taken through modified 15 forms of the burner. Figs. 8 and 9 are perspective and vertical sections, respectively, of another form of burner embodying my invention; and Fig. 10 is a perspective view showing the grouping of several burner-tips 20 on a single burner.

In carrying out my invention I have found that in order to produce a flat, uniform, and at all times smokeless flame in burning acetylene gas and other gases which are rich in 25 hydrocarbons it is necessary that the width of the slot in the burner-tip shall be of not more than fourteen one-thousandths ($\frac{14}{1000}$) of an inch and that the depth of the slot must be less than thirty one-thousandths ($\frac{31}{1000}$) of an 30 inch and that the radius of the slot must in no case exceed three-sixteenths ($\frac{3}{16}$) of an inch, and I have also discovered that there must exist an exact relationship between the 35 width of the slot, the radius of the slot, the depth of the slot, and the position of the gas-chamber and that a change in either of these will necessitate corresponding changes in the others. I have also found that in the construction of the burner it is essential that a 40 hollow gas-chamber must be provided immediately below the slot. This chamber, however, may be arranged upon either one or both sides of the slot, as may be preferred.

In constructing the burner I preferably use 45 the material known as "lava," such as is commonly used in the manufacture of lava tips.

Referring to the accompanying drawings, it will be seen that in the construction of the burner illustrated in Figs. 1 to 4, inclusive, a 50 chamber A is provided, with which chamber the slot B communicates. The lower portion of the slot B, which communicates directly with the gas-chamber A, is exceedingly contracted, it being of a width not exceeding fourteen one-thousandths ($\frac{14}{1000}$) of an inch; but 55 for the purpose of more clearly illustrating the construction I have in the drawings shown the slot of relatively greater width. It will be observed that at a point which is substantially 60 thirty one-thousandths ($\frac{31}{1000}$) of an inch above the gas-chamber A a V-shaped recess communicates at its apex with the slot, so as to produce a seat for the flame upon the tip of the burner a considerable distance above 65 the exceedingly-contracted slot for the passage of the gas, the object of this construction being to obviate the possibility of the

gas-passage becoming clogged by deposition of carbon, as, owing to the fact that the slot is so exceedingly contracted, would otherwise 70 be likely to occur.

It is at once evident that gas-burners involving the essential and necessary features of my invention are subject to numerous modifications without departing from the spirit of 75 my invention. I have in Figs. 5 to 9, inclusive, illustrated some of these modifications. It will be observed upon reference to said figures that in all of them the essential features—i. e., the contracted slot B, the gas-chamber A adjacent thereto, the walls of a thickness depending upon the width of the gas-slot, and the widened opening B' above the slot to insure a seating of the flame at a point removed from the slot, as described in connection with the construction shown in Figs. 80 1 to 4, inclusive—are shown.

My experiments have demonstrated that a deviation in the construction of the burner from the relative dimensions of the slot as to 90 its width and radius, the thickness of the walls of the slot, or the position of the gas-chamber relative to the slot will result in the production either of a smoking or imperfect flame, depending, of course, upon the change 95 that is made in the construction of the burner. I have also found that if any of the dimensions above-specified are increased beyond the limit specified herein an imperfect and smoking flame is produced, and in order in burning acetylene gas to produce a flat, uniform, and smokeless flame under all the varying degrees of gas-pressure to which the burner may be subjected it is absolutely necessary that in the construction of the burner the dimensions which I have specified be rigidly adhered to. I have found that the same results are obtained by the use of either of the 100 modified forms of burners illustrated in the accompanying drawings, and my object in 105 showing these modifications is mainly to illustrate the simplicity of construction. For instance, in constructing the burner shown in Figs. 1 to 4, inclusive, it is simply necessary to bore a hole transversely through the tip to 110 form the gas-chamber, the ends of the hole being afterward plugged, as shown in Fig. 3. The vertical gas-passages are then bored upward from the base of the tip. From this 115 description the means of producing the other 120 forms of burners shown will be at once apparent.

Having thus described my invention, what I claim to be new, and desire to secure by Letters Patent, is—

1. A burner-tip for acetylene gas, the same consisting of a body portion provided with a gas-chamber, a gas-passage communicating with said chamber, a slot leading outward from said chamber, said slot having a width 130 of less than fourteen one-thousandths ($\frac{14}{1000}$) of an inch, a radius of less than three-sixteenths ($\frac{3}{16}$) of an inch, and having a depth 135 of less than thirty one-thousandths ($\frac{31}{1000}$) of

an inch, substantially as described, and for the purpose specified.

2. A burner-tip for acetylene gas, the same consisting of a body portion provided with a gas-chamber, a gas-passage communicating with said chamber, a slot leading outward therefrom, said slot having a width of less than fourteen one-thousandths ($\frac{14}{1000}$) of an inch, a radius of less than three-sixteenths ($\frac{3}{16}$) of an inch, and a depth of less than thirty one-thousandths ($\frac{31}{1000}$) of an inch, the side walls at the upper extremity of the slot being beveled outwardly to form a seat for the

flame, of greater width than the slot, substantially as described, and for the purpose 15 specified.

3. A gas-tip of the dimensions described in combination with a gas-chamber intersecting at right angles the gas-outlet, said gas-chamber being of greater length than width. 20

In testimony whereof I affix my signature in presence of two witnesses.

EDWARD J. DOLAN.
